Primary Examiner — Terry A Wallace(74) *Attorney, Agent, or Firm* — Dunlap Codding, P.C.(57) **CLAIM**

The ornamental design for a beverage coaster, as shown and described.

DESCRIPTION

FIG. 1 is a perspective view of a beverage coaster showing my new design.

FIG. 2 is a front view thereof, the rear view being a mirror image.

FIG. 3 is a side view thereof, the opposite side being a mirror image.

FIG. 4 is a top plan view thereof.

FIG. 5 is a bottom plan view thereof.

FIG. 6 is a perspective view of an alternate embodiment of FIG. 1.

FIG. 7 is a front view of FIG. 6, the rear view being a mirror image.

FIG. 8 is a side view of FIG. 6, the opposite side being a mirror image.

FIG. 9 is a top plan view of FIG. 6; and,

FIG. 10 is a bottom plan view of FIG. 6.

The broken lines shown in FIGS. 1-3 and 5-6 are for purposes of illustrating environment only and form no part of the claimed design.

1 Claim, 6 Drawing Sheets(56)
